UNITED STATES PATENT OFFICE.

MORRIS P. HOLMES, OF CLAREMONT, NEW HAMPSHIRE, ASSIGNOR, BY MESNE ASSIGNMENTS, TO THE JEFFREY MANUFACTURING COMPANY, OF COLUMBUS, OHIO, A CORPORATION OF OHIO.

MINING MACHINE.

Application filed November 24, 1916. Serial No. 133,144.

To all whom it may concern:

Be it known that I, MORRIS P. HOLMES, a citizen of the United States, residing at Claremont, in the county of Sullivan, and

5 State of New Hampshire, have invented certain new and useful Improvements in Mining Machines, of which the following is a full, clear, and exact specification.

My invention relates to mining machines.

10 It has for its object to cool the cutting mechanism of such a machine in an improved manner whereby all question as to danger of igniting the gas in the mine, arising from the high temperature of the cutter bits, is

15 eliminated. A further object of my invention is to provide an improved cutter bar for such machines wherein a cooling agent is supplied longitudinally of the bar in an improved manner and so distributed

20 to the cutter chain and cutter bits as to maintain the same relatively cool and thus effectually prevent such ignition of the mine gases as is said to occur as a result of the bits becoming red hot during the cutting

25 operation. Another object is to provide a mechanism whereby the delivery of masses of dust in the air, from the kerfs to the rooms or entries of the mine will be prevented. These and other advantages of my improved

30 construction will, however, hereinafter more fully appear.

In the accompanying drawings, I have, for purposes of illustration, shown a plurality of embodiments which my invention may

35 assume in practice, illustrating the same in connection with a shortwall machine of the continuous cutter type, although it will be understood that my invention is not limited

40 to use on that type of machine, the same being shown herein only for purposes of illustration.

In these drawings,—

Fig. 1 is a plan view of a machine equipped with my improvement, certain parts of the 45 cutter bar being broken away to facilitate illustration.

Fig. 2 is a central longitudinal section of the cutter bar and machine shown in Fig. 1.

Fig. 3 is a transverse sectional view on 50 line 3—3 of Fig. 2.

Fig. 4 is a transverse sectional view on line 4—4 of Figs. 1 or 2.

Fig. 5 is a transverse sectional view on line 5—5 of Fig. 1.

Fig. 6 is a transverse sectional view on 55 line 6—6 of Fig 1.

Fig. 7 is a view similar to Fig. 5, showing a modified construction.

Fig. 8 is a similar view showing a still further modified construction. 60

Fig. 9 is a view similar to Fig. 5, showing another modified construction.

Fig. 10 is a perspective view, partially in section, showing another modification.

Fig. 11 is a transverse sectional view, 65 showing a modified form of the invention applied to a bar of the type shown in Fig. 10.

Fig. 12 is a plan view of the parts at the inner end of the cutter bar.

In the illustrative construction, Figs. 1 to 70

6, I have shown a machine 1 of the type having a sliding rigid cutter bar 2 projecting from the front end thereof and adapted to be projected in under the coal during the sumping cut, and thereafter moved trans-

75 versely of the coal face to undercut the coal, the machine being propelled by suitable feeding mechanism of a well known character.

Around the outer end of this cutter bar 2 is movable on suitable sprockets, a cutter 80 chain 3 provided with a plurality of upper and lower cutter bits 4 adapted, as usual, to extend above and below the lines of the cutter bar 2.

This cutter bar 2 may be integral or made 85 up as desired and is provided with a longitudinally disposed chamber 5 preferably within the confines thereof. As shown, this chamber is preferably formed between the top and bottom of the bar, as, for instance,

90 between the plates 6 and between the sides thereof, as, for instance, between the side members 7; chain guides, as, for instance, the members 8, being disposed in inverted relation at the sides of the members 6, and the 95

several elements, where the bar is of plural part construction, being rigidly connected together by any suitable means in a well known manner. As shown, this chamber 5 extends longitudinally of the bar 2 from a 100

point adjacent the front end of the machine to a point adjacent the front end of the bar, and acts as a fluid conduit adapted to receive a cooling agent from a suitable source and

deliver the same in a manner hereinafter described, to the cutter bits 4.

In the form of my invention shown in Figs. 1 to 6, a cooling agent, as for instance

air or water, and preferably water, is supplied to the machine by means of a pipe connection 9 communicating with a suitable passage 10 formed in the head 11 of the machine. This passage, in turn, extends transversely to a point preferably above the center of the bar 2, and there communicates with a short, vertically disposed passage 12 formed on an upwardly extending bored out and 10 suitably packed extension 13 on an adjusting screw-receiving nut 14, pivoted on the machine 1 and of usual construction, and which is disposed longitudinally of the bar and within the latter and adapted to be used 15 whenever it is desired to adjust the bar longitudinally relative to the machine, as for instance when taking up slack in the cutter chain. The devices for pivoting the part 14 comprise the apertured arms 14^b, at the end 20 of the part 14, the apertured eye 14^c and the hinge or pivot pin 14^d, see Figs. 2 and 12. As shown, this nut 14 is provided with a longitudinally extending opening 15 therein having threaded walls 16 adapted to receive 25 the threaded end 17 of a bar adjusting screw movable with the bar relatively to the thread 15 and the nut 14 adjustable from the exterior of the bar by means of an enlargement or cylindrical boss 18, all in a well known 30 manner. This screw is herein provided with a longitudinally disposed passage 19 communicating with the chamber 5. In a preferred construction, the front end of this adjusting screw also extends through a split 35 block 14^a riveted to the bar, spaced with respect to the nut 14 and herein shown suitably packed at 20, the adjusting screw also being provided with a flange 21 surrounding the bore in the block. It will be seen that 40 the part 14 remains stationary relatively to the main frame of the machine and that the rotary element, having the threaded end part 17 and the operating enlargement 18, will move forward when rotated, and push 45 the cutter bar forward correspondingly; there being a passage for fluid through these elements. Any suitable cooling fluid, and preferably water, which is supplied to the pipe 9, is thus conveyed through the adjusting screw 17 into the chamber 5, so that when 50 the end of that chamber is plugged, as for instance by fixing a wooden plug 22 suitably packed at 23, near the front end thereof, a considerable pressure may be developed in 55 this chamber.

From this chamber the fluid is in turn distributed to the cutter bits in such a manner as to cool them effectually, the fluid being played directly or indirectly thereon. In a 60 preferred form of my invention (Fig. 5), a plurality of longitudinally spaced, oppositely disposed, lateral outlets 24 leading from the chamber 5, are provided in the upper part of the bar and preferably slightly 65 removed from its front end. As shown,

these outlets are directed at such an angle relative to the bar that the fluid under pressure in the chamber 5 will be brought into contact with the upper bits, as for instance by being deflected by the upper wall of the 70 cut over the outer edge of the chain guides 8 and onto the upper bits 4. Obviously, these outlets may, however, be arranged in any desired manner and in any desired place on the bar or on either side of the latter 75 without departing from the spirit of my invention, and any desired number of the same may be used in the cutter bar or any of the members forming the cutter bar, so long as the fluid is distributed to the upper cutter 80 bits. To cooperate with these outlets 24, I also preferably provide in the side member 7 of the bar, suitable horizontally disposed outlets 25 adapted to direct the fluid under pressure in the chamber 5 against the chain 85 3 as it moves along between the guides 8 and between the links in the chain, in such a manner as to supplement the action of the outlets 24. Thus, it will be noted that not only will the upper bits be subjected to the cooling agent, but that the chain itself will be played upon by the cooling agent, and that a part of the latter will find its way through the chain to the bits, while all of the same will tend to drop to the bottom so that the 90 lower bits 4 will run therein and thereby be effectually cooled.

In the form of my invention as shown in Fig. 7, it will be noted that instead of having the fluid delivered through a central 100 chamber 5 in the bar, the same is there delivered through one or more chambers 26 formed in one or both of the side members 7, and that these chambers communicate with outlets 27 formed in one or both of the 105 guard members 8. In this construction, it will be noted that the fluid will also be delivered to the upper bits, but that the point of delivery of the outlets is located closer to the bits than is the case in the construction shown in Figs. 1 to 6. It will, of course, be obvious that this form of construction may be readily adapted to use in connection with bars other than those having a central chamber therein, as for instance those bars 110 where the members 7 are spaced apart. Obviously, in such a construction, the fluid may be conducted to the chambers 26 in any suitable manner.

In the forms of my invention shown in 120 Figs. 8 and 9, it will be noted that I have illustrated in Fig. 8 a bar of substantially the same construction as that shown in Fig. 5, but that in this instance the fluid is delivered from the chamber 5 into a plurality of 125 passages 28 extending through the top plates 6 and communicating with suitable horizontally disposed passages 29 formed in the guide members 8. Obviously, by the use of such a construction, the fluid will be deliv- 130

ered directly onto the upper bits without the necessity for being deflected onto the same by the top of the cut. It is also obvious that in such a construction, I may, if desired, provide the lower plates with similar passages 28 and 29, as shown. In the form of my invention shown in Fig. 9, it will be noted that I have shown a construction closely similar to that illustrated in Fig. 8, 10 and likewise comprising passages 28 and 29, but that in this instance the bottom, side, and guide members are formed integral, the top plate 6 being the only separate plate.

In the construction shown in Fig. 10, attention is also directed to the fact that I have there shown in perspective, in partial section, one-half of another type of cutter bar of a well known construction. In this bar, it will be noted that a member 30 of 20 I-beam section is disposed on its side on a bottom plate 31 and covered by a top plate 32, these plates 31 and 32 also acting as chain guides and being provided with guide surfaces 33 for that purpose. In such a construction, the fluid may, obviously, be supplied to one or both of the vertically central chambers 34 and 35 formed by the web of the member 30, and the fluid may pass out from these chambers to the cutter chain and 30 bits through suitable outlets 36 in the walls adjacent the chain. Obviously, in this construction, if desired, inclined outlets similar to the outlets 27 or outlets similar to the outlets 28 and 29 above described, may also 35 be used, if desired, either alone or in co-operation with outlets of the type shown at 36, the several outlets being shown in Fig. 11. Obviously, the cross section of any 40 of the outlets mentioned in any form of my improvement described herein may be varied within wide limits without departing from the spirit of the invention.

In the use of my improved construction, it will be noted that when the cooling agent 45 is delivered to the chamber 5 or the other chambers disposed longitudinally of the bar, the same will be ejected therefrom through a plurality of outlets disposed longitudinally of the bar and transversely with respect 50 thereto, which act to deliver the cooling agent directly or indirectly to the chain, the upper cutter bits, the lower cutter bits, or to all of those elements, both before and after the chain has rounded the end of the 55 bar, and in such a manner as to maintain the bits at the desired minimum temperature. Thus, I effectually prevent any ignition of gas pockets or the like which may exist in the coal, and which it is stated that 60 the heated bits cause to be exploded. Attention is also directed to the fact that in the use of my improved construction, it is possible to utilize an adjusting screw of standard construction, and bars of standard construction, by only minor changes in the

same, thereby adapting the invention to a wide range of usefulness in machines of standard construction already in the field. It should also be noted that, due to my improved method of conducting the cooling 70 agent into the chamber, waste of the latter is also effectually prevented at the same time that the connections thereto are amply protected against injury by the head of the machine, either as the machine moves into the 75 coal during the sumping cut or transversely with respect thereto during the cut across the face. It will, of course, also be obvious that whenever it is unnecessary to use the cooling agent for the cutter bits, as for instance in mines relatively free from gas, the same machine may be used without any inconvenience whatsoever, it only being necessary to disconnect the source of supply and then unscrew the pipe connection 9 and 80 preferably insert a suitable plug in place of the same. Not only are the cutters and adjacent apparatus kept cooled and below that point in temperature where there would be 85 danger of their igniting gas but, supplementing that, the jets of water can be so delivered that they and the spray resulting from them will operate to lay the dust which the cutters tend to form and to throw 90 into the air in the room. This is often done to such an extent, and the dust is formed in such volumes that it is carried comparatively long distances from the kerfs, and is deposited upon the floor, the walls and roof 95 of the various rooms and entries. Then 100 when the various conditions such as the proper proportions of atmospheric oxygen and dust are favorable, rapid combustions of the dust can be started, and explosions are caused. In the present mechanism the 105 spraying devices are so disposed and arranged relatively to the other parts that liquid spray is being delivered at all times 110 on lines transverse to the cutter bar and parallel to the coal face, over the entire area which is covered by the bar and the cutters. Consequently there is a supply of spray at all points where gas pockets will be struck and at points where dust will be generated, either at the time of cutting the coal from its 115 bed, or by subsequently agitating it and stirring it up in the form of slack after it has been dislodged.

In some machines of this general class all of the cutting is done while the active cutters are traveling along a line parallel to the coal face and at the inner end of the cutter carrying arm or frame. With machines of this subclass this cutting line is constantly advancing inward further and further from 125 the face.

The chain links with their cutters travel backward from one end of the cutting line for several (often six to eight) feet to the driving mechanism without contacting, 130

along the side of the machine, with the coal in its native position, but nevertheless engaging with the loose slack in the kerf; and then they travel forward again to the other end of the cutting line, without contacting with the solid coal, but engaging with the slack on the bottom of the kerf. And as they travel thus backward and forward through the outer part of the kerf they engage with, stir up and agitate the fine cuttings behind the line of cut, and create volumes of dust in the outer part of the kerf, and in that region of the outside room which is adjacent to the mouth of the kerf.

15 The machine herein illustrated typifies another subclass within the general class. In those of the latter sort the cutters are so arranged that the greater part of their work is done while the chain is advancing laterally, the machine at such time moving bodily along, and parallel to, the outer vertical face of the coal. Here the line of cut is at right angles to the coal face and the cutters as they leave the outer end of their cut, are 25 immediately drawn out into the room, carrying with them large quantities of comminuted and dusty slack. And those cutters which are returning along the other side of the cutter carrier to their work tend to engage with, agitate and stir up such fine cuttings as remain within the kerf.

In order to keep all of the cutters cool as above described, and also effectually prevent the forming of dust clouds, both at the 35 points where the cutters are tearing off small particles of coal and at the points where the idle cutters are engaging the loosened slack, and to settle the dust in the region where the cutter bar is positioned, the 40 liquid spray should be formed and distributed constantly through that entire region, that is, delivered at points in all of the vertical lines between the face of the coal and the inner end of the cut.

45 It has been proposed to deliver liquid jets at points along the inward advancing line of cut parallel to the coal face, formed in the way characteristic of machines of the first aforesaid class. My object is to supply jets 50 and spray continuously during the cutting operation through the entirety of that part of the kerf in which is positioned the cutter carrier and the cutters, for effectually settling the dust and keeping the mechanism cool; and to provide devices for accomplishing 55 these purposes in machines of either of the subclasses referred to.

With a machine of the sort here illustrated, when the cutter bar is advancing longitudinally into the coal (that is, while 60 "sumping") the jets and the spray cloud are effective at the mouth of the kerf as well as at the inner end of the cut. Then while the cutting mechanism is normally op-

erating and is being advanced bodily on lines 65 parallel to the coal face, there are jets projected laterally on practically all lines transverse to the cutter bar and along its length, this not only catching the dust which is on the front side, but also that on the rear side, 70 which may be formed by the idle cutters picking up or agitating the slack. These and other advantages of my improved construction will, however, be clearly apparent to those skilled in the art. 75

While I have, in this application, specifically described several embodiments which my invention may assume in practice, it is to be understood that the forms thereof shown herein are used only for purposes of 80 illustration, and that the invention is adapted to use on machines of various other types and to be modified and embodied in various other forms without departing from its spirit, it being my intention to include all 85 such uses of the invention within the scope of the appended claims.

What I claim as new and desire to secure by Letters Patent is:

1. In a mining machine, a cutter bar having a longitudinally disposed enclosed vertically central, fluid conducting chamber therein and a series of laterally extending communicating outlets and a cutter chain movable around said bar. 90

2. In a mining machine, a cutter bar having a longitudinally disposed enclosed vertically central, fluid conducting chamber therein and a series of laterally disposed communicating outlets intermediate its ends 100 and a cutter chain movable around said bar.

3. In a mining machine, a cutter bar having a longitudinally disposed enclosed vertically central, fluid conducting chamber therein and a series of upwardly and laterally 105 disposed communicating outlets intermediate its ends and a cutter chain movable around said bar.

4. A flat mining machine cutter bar presenting cutter chain guiding surfaces on its 110 edges and having a longitudinal fluid conducting chamber within its vertical limits and between said guiding surfaces and laterally extending outlets communicating with said chamber. 115

5. In combination, a flat mining machine cutter bar of a cross section presenting cutter chain guiding surfaces and a longitudinally extending passage within the vertical limits of said bar and between certain of 120 said surfaces, and means for converting said passage into a fluid distributing chamber including outlets discharging toward the bar periphery.

6. In a mining machine, a cutter bar, a 125 cutter chain movable around the same and having upper and lower bits thereon, and means disposed within said bar for deliver-

ing fluid in a plurality of series of jets distributed along said bar to deliver fluid to said upper bits both while they are moving outward and while they are moving inward.

5 7. In a mining machine, a cutter bar comprising spaced side members and top and bottom members disposed over and beneath the same to form a conduit, means for delivering fluid between said side members and
10 laterally therethrough and a cutter-carrying chain traveling in the horizontal planes of the conduit around said bar.

the conduit around said bar.

8. In a mining machine, a cutter bar comprising spaced side members and top and bottom members disposed over and beneath the same to form a conduit, means for delivering fluid between said side members and laterally through said top member, and a cutter carrying chain traveling in the horizontal planes of the conduit around said bar.

9. In a mining machine, a cutter bar, and a cutter chain carrying bits and movable on said bar, said bar having a central longitudinally disposed enclosed chamber therein
25 and positioned in the horizontal planes of said chain and oppositely extending communicating outlets delivering fluid to said bits.

10. In a mining machine, a cutter bar,
30 and a cutter chain carrying bits and movable on said bar, said bar having a longitudinally disposed chamber which is central, vertically, in relation to the top and bottom planes of the bar and separate communicat-
35 ing outlets delivering fluid directly to said bits and directly to said cutter chain.

11. In a mining machine, a cutter bar comprising spaced side members and top and bottom members and cooperating chain 40 guiding members, a chain movable in said guiding members and having upwardly extending bits, and passages for delivering fluid through the opposite sides of said bar to said bits.

45 12. In a mining machine, a cutter bar, and a cutter chain carrying upper and lower bits and movable on said bar, said bar having a longitudinally disposed chamber which is positioned centrally, vertically, in
50 relation to the top and bottom planes of the bar and having upwardly and laterally extending outlets for directing fluid against said upper bits.

13. In a mining machine, a cutter bar,
55 and a cutter chain carrying bits and movable on said bar, said bar having a longitudinally disposed chamber formed therein and positioned centrally, vertically, in relation to the top and bottom planes of the bar and
60 having outlets for continuously directing fluid against the entire upper wall of the cut and adjacent said bits.

14. In a mining machine, a cutter bar, a cutter chain carried on said bar movable

around the end of the same, a duct positioned centrally, vertically within said bar for delivering fluid longitudinally thereof, and means for delivering fluid therefrom laterally to said chain after the latter has rounded the end of said bar and along the side thereof. 65 70

15. In a mining machine, a cutter bar, a cutter chain movable around the end of the same, means disposed within the confines of said bar for delivering fluid longitudinally thereof, and means for delivering fluid therefrom laterally to said chain both before and after the latter rounds the end of said bar and along the sides of the bar to the points where they enter the material being cut. 75 80

16. In a mining machine, a cutter bar having a longitudinally extending duct positioned centrally, vertically, relatively to the top and bottom planes of said bar, a cutter chain traveling around said bar in the horizontal planes of the said duct, means closing one end of said duct, means for delivering fluid into said duct, and laterally disposed means spaced apart longitudinally of said duct on transverse lines intermediate of the ends thereof for delivering fluid laterally therefrom in a series of jets extending to the face of the material being cut. 95

17. In a mining machine, a cutter bar having longitudinally disposed fluid conducting means formed therein, cutter chain guiding members on said cutter bar, a cutter-carrying chain traveling around said bar in the planes of the said fluid conducting means, and means for delivering fluid laterally from said conducting means through the outer edges of said chain guiding members and along lines inclined to said outer edges. 100 105

18. In a mining machine, a frame, a cutter bar, a cutter chain thereon, ducts for delivering fluid to the bits of said chain, means for adjusting said bar, relatively to 110 said frame and adapted to permit the passage of fluid therethrough, and means for supplying fluid through said adjusting means to said delivering ducts.

19. In a mining machine, a machine frame, a cutter bar thereon, a cutter chain on said bar, ducts for delivering fluid to the bits of said chain, means for adjusting said bar relative to said frame and adapted to permit the passage of fluid therethrough, and means for supplying fluid through said adjusting means to said delivering ducts. 115 120

20. In a mining machine, a machine frame, a cutter bar thereon, a cutter chain on said bar, ducts for delivering fluid to the bits of said chain, means for adjusting said bar relative to said frame and adapted to permit the passage of fluid therethrough, 125

and means including fluid passages in said frame communicating with the passageway through said adjusting means for supplying fluid through said adjusting means to said 5 delivering ducts.

21. In a mining machine, a machine frame, a cutter bar having a longitudinally extending chamber therein, a screw for adjusting the cutter bar relatively to the frame 10 and having a passage extending therethrough communicating with said chamber, a threaded nut into which said screw is threaded having a passage therein communicating with the passage in said screw where- 15 by fluid delivered to the passage in the said nut can pass through the said screw and the said chamber.

22. In a mining machine, a cutter bar having a chamber therein closed at one end 20 and having a series of lateral outlets, an adjusting screw having a passage extending therethrough and communicating with said chamber, and a screw receiving nut disposed in the opposite end of said chamber having 25 a passage therein communicating with the passage in said screw.

23. In a mining machine, a machine frame, a cutter bar having a longitudinally disposed chamber therein having a plurality 30 of lateral outlets, a cutter chain on said bar, an adjusting screw having a passage communicating with said chamber, and a nut carried on said frame and receiving said

screw having a passage therein communicating with the passage in said screw.

24. In a mining machine, a cutter bar having a longitudinally extending chamber therein and a series of oppositely disposed longitudinally spaced laterally extending outlets, a cutter carrying chain movable on 40 said bar, an adjusting screw having a passage extending therethrough and communicating with said chamber, a threaded nut into which said screw is threaded having a passage therein communicating with the 45 passage in said screw, a machine frame, and means for delivering fluid through said frame into said passages.

25. In a mining machine, a cutter bar having a longitudinally extending chamber 50 therein closed at one end and having a series of oppositely disposed longitudinally spaced laterally extending outlets, a cutter carrying chain movable on said bar, an adjusting screw having a passage extending therethrough and communicating with said chamber, a threaded nut disposed in the opposite end of said chamber and into 55 which said screw is threaded having a passage therein communicating with the passage in said screw, a machine frame, and means for delivering fluid through said frame into said passages.

In testimony whereof I affix my signature.

MORRIS P. HOLMES.
